INSTALLATION BRACKET FOR VENETIAN BLINDS

Paul J. Harris, Portland, Oreg.

Application April 17, 1943, Serial No. 483,377

4 Claims. (Cl. 160—34)

This invention relates generally to Venetian blinds, and particularly to an installation bracket for Venetian blinds.

The main object of this invention is to provide an exceedingly simple and rigid form of installation bracket for Venetian blinds.

The second object is to provide a bracket by means of which the head rail can be easily and accurately adjusted for height at both ends without detracting from the appearance of the bracket.

The third object is to provide a bracket of the class described having an outside facia board to prevent the passage of light above the blind, and also to conceal the mechanism of the blind as well as any irregularities in the spacing above the head rail occasioned by adjustment of the blind to provide a perfect adjustment of the lower rail with relation to the window sill, such irregularity being due to the inaccuracies in the window frame itself, or in the construction of the blind, or in the fastening of the supporting tapes, or to changes in the length thereof after manufacture.

The fourth object is to construct the bracket so as to obtain the maximum amount of strength with the minimum amount of expenditure for material and labor for manufacture and assembly.

These and other objects are accomplished in the manner set forth in the following specification, as illustrated in the accompanying drawings, in which:

Fig. 1 is a vertical section taken along the line 1—1 in Fig. 3.

Fig. 2 is a vertical section taken along the line 2—2 in Fig. 1.

Fig. 3 is a plan showing the head rail and front and rear facia boards broken away.

Fig. 4 is a fragmentary section taken along the line 4—4 in Fig. 1.

Similar numerals refer to similar parts throughout the several views.

Referring in detail to the drawing, there is shown the bracket for the left side of the window frame as viewed from the interior. This bracket consists mainly of a flat plate 10 having the in-turned vertical edge 11 whose lower end 12 is turned horizontally and provided with the up-turned tab 13. The outer facia board 14 rests upon the member 12 and against the inner side of the edge 11.

Hingedly attached to the plate 10 by means of a rivet 15 is the angle plate 16 whose vertical edge 17 is normally parallel with the edge 11. 55

The edge 17 is turned outwardly along the lower end 18 to support the inner facia board 19, which is held against the edge 17 by the inturned tab 20.

A depression 21 made by a center punch forms a convenient latch for the upper end of the member 16. Holes 22 are provided in the plate 10 as well as in the edge 11 for fastening purposes.

Mounted against the inner side of the plate 10 is a vertically movable slide 23 which is held in place by the guide 24, preferably spot welded to the plate 10. The upper edge of the guide 24 is out turned to form an ear 25, and has freely passed therethrough the vertical adjusting screw 26 whose head 27 is on the under side of the ear 25. A nut 28 is placed on the screw 26 on the top side of the ear 25, and is prevented from turning by contact with the slide 23.

On the upper end of the slide 23 is secured a channel 31 between whose lower side 32 and upper side 33 is placed the head rail 34. The upper side 33 is made long enough to serve as a stop for the upper portion of the facia board 14.

The upper end 29 of the screw 26 is reduced and extends through the lower channel side 32 and is loosely riveted thereto in order that the screw may turn.

When installing the device, a pair of the plates 10 are installed at opposite sides of the window frame, and the inner facia board 19 is swung up on the rivets 15, making it possible to easily insert the head rail 34 between the sides 32 and 33 of the channel 31, and then permit the facia board 19 to drop down and conceal the mechanism.

It is commonly found that when a blind is installed, the lower rail (not shown) either touches the sill or is spaced too far therefrom. With my construction, this difficulty can be overcome by simply rotating one or both of the screws 26 as the case may be, in order to bring the lower rail into perfect parallelism with the sill of the window. Once adjusted, it is obvious that no further attention will be required, and that the need for extreme accuracy in measurement of the blind is dispensed with. Moreover, objectionable light leaks at the upper edge of the blind are avoided, and the external appearance of the blind improved by the presence of the outer facia board.

It must be understood that a pair of these devices is required in each installation, and these must be right and left in order to meet the conditions.

It will also be noted that by swinging the front

facia board 19 upwardly, the introduction of the head rail into the channel 31 is much simplified.

In some cases, it will be found desirable to hinge the facia board 19 downwardly. To do this, it is merely necessary to reverse the position of the rivets 15 and the countersinks 21.

It is a well known fact that fastening ears are often applied on the upper ends of the brackets for use when the bracket is to be fastened at the upper portion of the window frame. These have been omitted from the present illustration as they form no part of this invention.

While I have thus illustrated and described my invention, it is not my intention to be limited to the precise form, but I do intend to cover all such forms and modifications as fall fairly within the appended claims.

I claim:

1. An installation bracket for Venetian blinds consisting of a plate adapted to be secured to a window frame, a shelf mounted on said plate for supporting the head rail of a blind, and means for adjusting said shelf vertically.
2. A device of the class described consisting of a plate adapted to be attached to a window frame, a vertically adjustable support for the head rail mounted against said plate, a fixed facia board supported at the outer edge of said plate by means of said adjustable support.
3. A device of the class described consisting of

30

a vertical plate adapted to be attached against the side of a window frame, a horizontal channel slidably mounted on the inner side of said plate, a slide for guiding said channel, a guide for said slide attached to said plate, a nut supported by said guide, and an adjusting screw extending upwardly through said nut to said channel whereby the rotation of said screw will change the elevation of said channel, said channel consisting of a support for one end of a head rail of a Venetian blind.

4. An installation bracket having in combination a vertical frame engaging plate adapted to be secured to a window frame normal to the window glass, the outer edge of said plate being in-turned, an outer facia board disposed against said in-turned edge, a vertically adjustable channel mounted along the inner upper side of said plate, the upper portion of said channel engaging said outer facia board, an angle plate hinged at its upper end to the interior edge of said first mentioned plate, said angle plate also having an in-turned edge, an inner facia board engaging said last mentioned in-turned edge, means for holding said inner facia board in position whereby said inner facia board may be swung upwardly in a manner to give access to the innermost end of said channel for the purpose of inserting a Venetian blind head rail therein.

PAUL J. HARRIS.
